COUNTING DEVICE

John Albertoli, San Francisco, Calif.

Application June 1, 1936, Serial No. 82,791

5 Claims. (Cl. 235—98)

My invention relates to a counting device, and particularly to a device for counting objects such as pieces of fruit prepared for canning.

It is among the objects of my invention to provide a counting device which is simple, inexpensive, and efficient; and which is particularly suited for counting halved fruit preparatory to canning the same.

The invention possesses other objects and features of advantage, some of which, with the foregoing, will be set forth in the following description of my invention. It is to be understood that I do not limit myself to this disclosure of species of my invention, as I may adopt variant embodiments thereof within the scope of the claims.

Referring to the drawing:

Figure 1 is a side elevation of a counting device embodying my invention, the near housing plate being removed, and parts being shown in section;

Figure 2 is a front elevation of the device illustrated in Figure 1; and

Figure 3 is an elevational view showing the left side of the device as shown in Figure 2.

Figure 4 is a perspective view of a modified form of the rotor.

In terms of broad inclusion, the counting device of my invention comprises a rotor having blades onto which objects to be counted are fed, the rotor and blades preferably being turned by the weight of the objects, and cooperating with a movable detent actuated by the objects to permit a step by step movement of the rotor for advancing the blades successively to object receiving position. A counter is actuated in accordance with the movement of the rotor for indicating the number of objects fed therewith.

In terms of greater detail, the counting device of my invention comprises a rotor 1 provided with a plurality of blades 2 and mounted upon a shaft 3 journaled between a pair of housing plates 4 held in spaced relation by a plurality of spacing rods 5. The blades are of a size suitable for receiving a single object, such as a half pear or peach.

The movement of the rotor 1 is controlled by a suitable detent comprising an arm 6 pivoted between the plates 4 above the rotor, and arranged to extend into the path of movement of the blades 2 to form an abutment limiting the movement of the rotor in one direction. The arm 6 is provided with a weighted portion 7 by which the arm is normally held by gravity against a stop 8.

A lever 9 is connected to the detent arm 6 for moving the arm 6 out of the path of the blades 2, said lever 9 extending into the path of objects fed

onto the blades 2. The objects to be counted are directed onto the rotor blades 2 by any suitable means, as for example a chute or slide 11. As each object moves onto a blade 2, the lever 9 is displaced sufficiently to raise the arm 6 out of engagement with the next blade 2. The rotor turns under the load of the object, and as the object drops away from the lever 9, the detent arm 6 swings back into the path of the succeeding blade and blocks further movement of the rotor until the detent is again released.

A weighted arm 12, pivoted as at 13, is normally held by gravity against a stop 14 to prevent rotation of the rotor 1 in a reverse direction, the arm 12 being displaced by the blades as they are moved past the arm 12 in one direction, and then immediately dropping back onto the stop 14 to prevent movement of the rotor in the opposite direction.

A suitable counter, designated in general by the numeral 16, is arranged to be operated in accordance with the movement of objects past the rotor 1 for counting the objects. The counter 16 preferably comprises a plurality of counter disks 17, 18, 19 and 20 mounted upon shafts 21 between frame plates 22. The counter disks are preferably geared together in a desired gear ratio, and are driven by a pinion 23 upon the rotor shaft 3 meshing with gear teeth 24 upon the disk 17. The succeeding disks 18, 19, and 20 may be provided with similar gear teeth 24 meshing with pinions 25 carried by the preceding disks of the train, so that each disk is rotated by the preceding disk at a fixed ratio of movement.

The several disks are calibrated in accordance with the gear ratio of the toothed disks and their driving pinions. For a four bladed rotor a ratio of 10 to 1 is desirable. In that case, the first disk 17 may be calibrated in units from 0 to 40 with the disk 17 arranged to move through one unit for each quarter revolution of the rotor 1. The second disk 18, is then calibrated in intervals of 40 from 0 to 400; the third disk 19, in intervals of 400; and the fourth disk 20, in intervals of 4000. Pointers 26 are mounted upon one of the frame plates 22 in association with the calibrations of the several counter disks by which the disks may be read.

A gate 27 is preferably pivotally mounted between the plates 4 for directing objects from the rotor blades 2 onto a conveyor 28, or other suitable means for delivering the objects to a desired point of delivery. The gate 27 is preferably provided with a weighted arm 29, normally resting upon a stop 30, and permitting a limited swinging move-

ment of the gate as objects are carried therewith by the blades 2.

The counting device is particularly adapted for use in the canning of fruit such as halved pears or peaches. In this connection, the pieces of fruit are delivered onto the slide 11, either manually or by a suitable conveying means. As each piece moves downwardly along the slide 11 onto a blade 2, the detent arm 6 is displaced to momentarily free the rotor. As the rotor turns under the load imposed thereon by the fruit, the piece of fruit drops from under the lever 9, thereby permitting the arm 6 to drop back onto its stop 8 in time to engage the succeeding blade and prevent further rotation of the rotor until the detent is again tripped by another piece of fruit. In this manner, the rotor is advanced step by step to carry the blades successively into the fruit receiving position. The rotation of the rotor 1 operates through the pinion 23 to actuate the counter 16 for indicating the number of pieces of fruit delivered past the rotor.

The counting device may be mounted at any convenient station for keeping accurate count of the pieces of fruit passing therethrough. For example a counting device may be provided for each of the operators, or groups of operators, who initially halve the fruit for keeping count of the number of pieces of fruit prepared; or a counter may be arranged to keep a count of the pieces as they pass from one step to another in the canning process. The device may of course be used in similar manner in other connections where objects may be delivered onto the rotor blades for actuating the counting mechanism.

In the preferred embodiment of the device illustrated in the drawing, a partition 31 is mounted centrally between the housing plates 4. The blades 2 are formed with slots 32 to permit the blades to move past the partition; and the lever 9 is provided with a slot 33 arranged to receive the partition 31 with portions of the lever disposed on opposite sides of the partition.

In this arrangement, objects may be fed onto the rotor 1 upon either side of the partition 31. This permits the objects to be classified as to grade by the operator as the objects are delivered to the counting device. At the same time, an accurate count is made of the total number of objects fed past the rotor 1, irrespective of the grades of the objects. The objects, so classified and counted may be carried to separate points of delivery by the conveyor 28.

Figure 4 illustrates a modified form of the rotor wherein the partition 31 is carried by the rotor 1 itself. The partition 31 is located substantially midway between the sides of the blades 4 so that objects may be fed onto the blade portions on either side of the partition according to the grade of each object.

I claim:

1. A device for counting objects comprising a rotor provided with a plurality of blades upon which the objects may be directed and bodily supported for counting, the rotor being actuated by the weight of the objects, a detent controlled by the objects delivered onto the blades for limiting movement of the rotor, the detent being moved by objects fed onto one blade of the rotor for releasing the rotor and being arranged to be moved into the path of a succeeding blade for insuring the return of the detent to its initial position after each operation, means dividing each blade into a plurality of areas upon which the objects may be selectively fed, and a yield-

able guide adjacent the rotor and cooperating therewith for directing the objects along an arcuate path.

2. A counting device comprising a rotor provided with a plurality of blades arranged to successively receive objects fed thereto for counting and to be actuated by the weight of the objects for conveying said objects bodily to a point of delivery, a detent having a pair of diverging arms one of which normally blocks movement of the rotor and the other of which is arranged to be displaced by an object as it is fed onto the rotor for moving the first arm to release the rotor, said second arm being moved into the path of a rotor blade next approaching its object receiving position in such manner that said approaching blade cannot be moved to said object receiving position until the detent arms have been returned to their respective normal positions, and counting means actuated by the rotor for indicating the number of objects fed onto the rotor.

3. A counting device comprising a rotor provided with a plurality of blades arranged to successively receive objects fed thereto for counting and to be actuated by the weight of the objects for conveying said objects bodily to a point of delivery, partition means dividing the rotor blades into separate portions arranged to receive objects, a detent having a pair of diverging arms one of which normally blocks movement of the rotor and the other of which is arranged to be displaced by an object as it is fed onto the rotor for moving the first arm to release the rotor, said second arm being moved into the path of a rotor blade next approaching its object receiving position in such manner that said approaching blade cannot be moved to said object receiving position until the detent arms have been returned to their respective normal positions, and counting means actuated by the rotor for indicating the number of objects fed onto the rotor.

4. A counting device comprising a rotor provided with a plurality of blades arranged to successively receive objects fed thereto for counting and to be actuated by the weight of the objects for conveying said objects bodily to a point of delivery, a detent having a pair of diverging arms one of which normally blocks movement of the rotor and the other of which is arranged to be displaced by an object as it is fed onto the rotor for moving the first arm to release the rotor, said second arm being moved into the path of a rotor blade next approaching its object receiving position in such manner that said approaching blade cannot be moved to said object receiving position until the detent arms have been returned to their respective normal positions, a yieldable guide mounted adjacent the path of the rotor blades between the receiving and delivery points for retaining the objects upon the blades during movement between said points, and counting means actuated by the rotor for indicating the number of objects fed onto the rotor.

5. A counting device comprising a rotor provided with a plurality of blades arranged to successively receive objects fed thereto for counting and to be actuated by the weight of the objects for conveying said objects bodily to a point of delivery, partition means dividing the rotor blades into separate portions arranged to receive objects, a detent having a pair of diverging arms one of which normally blocks movement of the rotor and the other of which is arranged to be

displaced by an object as it is fed onto the rotor for moving the first arm to release the rotor, said second arm being moved into the path of the rotor blade next approaching its object receiving position in such manner that said approaching blade cannot be moved to said object receiving position until the detent arms have been returned to their respective normal posi-

tions, a yieldable guide mounted adjacent the path of the rotor blades between the receiving and delivery points for retaining the objects upon the blades during movement between said points, and counting means actuated by the rotor for indicating the number of objects fed onto the rotor.

JOHN ALBERTOLI.
